CLAIM

The ornamental design for a belt squat machine, as shown and described.

DESCRIPTION

FIG. 1 is a front, right, top perspective view of a Belt Squat Machine, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 1;

FIG. 11 is a partial enlarged view of FIG. 2;

FIG. 12 is a partial enlarged view of FIG. 2; and,

FIG. 13 is a partial enlarged view of FIG. 7.

The dashed broken lines in the figures are for the purposes of illustrating portions of the belt squat machine that form no part of the claimed design.

The dash-dot-dash broken lines are for notating enlarged views and form no part of the claimed design.
